(57) **CLAIM**

The ornamental design for a portion of a display screen with transitional icon, as shown and described.

DESCRIPTION

FIG. 1 is a front view of the first image in the sequence for a portion of a display screen with transitional icon showing our new design;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the sixth image thereof;

FIG. 7 is a front view of the seventh image thereof;

FIG. 8 is a front view of the first image of the design in FIG. 1 in the context of a different environment;

FIG. 9 is a front view of the second image thereof;

FIG. 10 is a front view of the third image thereof;

FIG. 11 is a front view of the fourth image thereof;

FIG. 12 is a front view of the fifth image thereof;

FIG. 13 is a front view of the sixth image thereof;

FIG. 14 is a front view of the seventh image thereof;

FIG. 15 is a front view of the first image of the design in FIG. 1 in the context of a different environment;

FIG. 16 is a front view of the second image thereof;

FIG. 17 is a front view of the third image thereof;

FIG. 18 is a front view of the fourth image thereof;

FIG. 19 is a front view of the fifth image thereof;

FIG. 20 is a front view of the sixth image thereof; and,

FIG. 21 is a front view of the seventh image thereof.

The dash-dot line illustrates the portion of a display screen, and the remaining broken lines illustrate portions of the transitional icon. None of the broken lines form part of the claimed design.

1 Claim, 9 Drawing Sheets
